LIMIT SWITCH

Marion E. Weeks, Bremerton, Wash.

Application February 27, 1939, Serial No. 258,693

4 Claims. (Cl. 200—47)

(Granted under the act of March 3, 1883, as amended April 30, 1928; 370 O. G. 757)

This invention relates to a limit switch, and has for an object to provide an improved limit switch especially intended for use on such equipment as cranes, hoists and conveyers, signal yard extensions, turret and gun training, gun elevating, steering gear, airplane elevators, shop equipment, etc.

A further object of this invention is the provision of a limit switch wherein spare parts and complete units are interchangeable, effecting appreciable savings in cost and weight of spares.

A further object of this invention is to provide a limit switch which may be assembled so as to be either a quick-make or a quick-break limit switch and with slight modification may be made as both a quick-make and a quick-break limit switch, depending upon the use to which it is to be placed.

With the foregoing and other objects in view, the invention consists in the construction, combination and arrangement of parts hereinafter described and illustrated in the drawings, in which,

Fig. 1 is a plan view of one form of limit switch in finished form of this invention, with the cover omitted.

Fig. 2 is a sectional view on line 2—2 of Fig. 1.

Fig. 3 is a fragmentary elevational view of the outside of the switch box, looking in the direction of arrow 3 at Fig. 4.

Fig. 4 is a sectional view on line 4—4 of Fig. 1.

Fig. 5 is a diagrammatic view of another form of limit switch, and

Fig. 6 is a diagrammatic view of a modified form of Fig. 5.

There is shown at 10 a switch box of suitable material provided with a cover 11 having an edge 12 for cooperating with a gasket 13 countersunk in the top of box 10. An opening 14 at one end of the box 10 permits the introduction of conductors 15 and 16 which are connected by means of bolts and nuts 17 to contact blocks 18 and 19, each provided with contacts 20 adapted to be bridged by a contact spring bar 21 to complete the circuit therebetween. The contact blocks 18 and 19 are each secured by means of the same bolts and nuts 17 to insulating base 22 which, in turn, is secured by stud screws 23 to bosses 24 extending from the bottom of the box 10. Another boss 25 has a condenser 26 secured thereon by a stud screw 27 and is electrically connected by conductors 28 to the bolts 17 to thereby prevent arcing and pitting of the contacts 20 with the spring contact bar 21 when the circuit therethrough is broken.

The spring contact bar 21 forms the head of a T-shaped spring bar whose leaf spring stem 30 is secured to the bight of a rocker 31 by a securing means 32, an insulating sheet 33 and molded insulation 34 so separating the rocker and T-stem and surrounding the securing means 32 that there is no electrical connection between the leaf stem spring 30 and the rocker 31. This rocker 31 is U-shaped in cross-section, the legs 35 thereof being apertured so as to be journaled on a pivoting pin 36 therethrough, this pin 36 also passing through aligned apertures in upstanding arms 37 of a bracket 38 secured to a boss 40 on the floor of the box 10 by nuts or stud screws 41.

As will be observed, the rocker 31 is fulcrumed on the journal pin 36 at a point closely adjacent the end 42 of the rocker, the distance between the fulcrum pin 36 and the rocker end 42 being approximately one-fourth the distance between the same fulcrum journal pin 36 and the T-head contact bar 21 extending from the other side of the rocker. A double coil spring 43 is wound around the pivot pin 36 and has one end 44 anchored against cotter pin 45 inserted across the bracket arms 37 and has its other end 46 resting against the bight of the rocker 31 adjacent the rocker end 42, tending to raise the T-head contact bar 21 to the position 21a.

Extending under the rocker end 42 is a lifter cam 47 and a breaker cam 48 which are generally circular except where the lifter cam 47 is provided with an angled wall 50 cutting a chord across the circular cam, while the breaker cam 48 is provided with a right angular notch 51, one side of which extends radially and the other side of which intersects a chord wall 52 thereon. The lifter cam and breaker cam are secured by a pin 53 in one of them cooperating with an arcuate slot 54 in the other of them so as to permit only limited relative angular movement between the cams and to cause simultaneous movement of the cams when the limit of relative movement has been reached. The breaker cam 48 is provided with a friction brake 55 extending part way around its periphery in the form of a leaf spring anchored at 56 to a side wall of box 10. The cam 47 is provided with an extending hub 57 through which is passed a shaft 58 in turn extending through a gland 60 and gland cover 61, on the side of box 10. The cam hub 57 is secured to the shaft 58 by means of a bolt and nut 62 which also serves as an anchor for one end of a coil spring 63, coiled about the hub 57 and anchored at its other end to a spring clip 64 secured by stud screw 65 to a boss 66 on the

box floor, and tending to rotate the lifter cam hub 57 and lifter cam 47 in a clockwise direction, as viewed in Fig. 2.

The breaker cam 48 is journaled on the same shaft 58, being caused to rotate on the shaft 58 within the limits permitted by the pin 53 and slot 54 by the friction brake 55, above described. A sleeve 67 between the breaker cam 48 and the side of the box 10 holds the breaker cam 48 in position adjacent the lifter cam 47, the sleeve 67 being pinned to the shaft 58 by a bolt and nut 68, one end of which serves as an anchor for a coil spring 70, whose other end is secured to a clip 71 secured in position by a stud screw 72, assisting the spring 63 in rotating the shaft 58, it being intended that either spring 63 or 70 may be strong enough alone to cause this rotation.

A stop lever 73 keyed on the shaft 68 exteriorly of the box 10 abuts against an abutment 74 forming part of a cover holding means 75. This cover holding means 75 cooperates with a bolt 76 extending through an apertured projection of the cover 11, there being four such cover holding means provided, one at each corner of the box.

A screw 78 and lock nut 80 provide means for adjusting the stopping position of the lever 73, thus adjusting the limit of rotation of the shaft 58. On the end of the shaft 58 is affixed a lever arm 81 having a bifurcated end 82 and carrying an axle 83 for a roller 84.

In operation, the limiting switch just described is set to act as a quick breaker switch for a mechanism such as an elevator, for instance. The switch box 10 with its assembled mechanism is placed in such a position that the roller 84 is in the path of some part of the elevator just as it reaches the end of its permitted path of travel, the current for operating the elevator motor in that direction being routed through the conductor 15, contacts 20, contact bar 21, and conductor 16. As the elevator rises and contacts the roller 84 it urges the lever 81 in a counter-clockwise direction. This causes rotation of the shaft 58, carrying with it the lever cam 47. The breaker cam 48 is held stationary by the friction brake 55 with the rocker end 42 pressing on the periphery of breaker cam 48, while the lifter cam 47 rotates a distance therebeyond slightly less than the length of the slot 54. As the rotation continues the pin 53 contacts the end of slot 54, thereby causing the breaker cam 48 to likewise move in a counter-clockwise direction, and rotating the periphery of breaker cam 48 until the angle notch 51 comes thereunder. Immediately that this happens, the double coil spring 43 pressing against the rocker end 42 rotates the rocker arm 31, and instantly moves the contact bar 21 to the position 21a, making a quick break of the circuit through conductors 15 and 16, arcing being prevented by the presence of the condenser 26 in the usual manner. The circuit is thus instantly broken, and the elevator operated thereby will naturally cease moving. When the elevator is operated in the opposite direction, as by the motor receiving current from another source so as to operate it only in the opposite direction, the lever 81 is allowed to be operated in a counter-clockwise direction as the pressure of the elevator brought against the roller 84 is released, due to the coil springs 63 and 70 tending to rotate the shaft 58 in a clockwise direction until the stop lever 73 prevents further movement.

At the commencement of this clockwise rota-

tion the breaker cam 48 is held against rotation while the angle wall 59 of the lifter cam 47 presses against the rocker end 42, causing the rocker end 42 to ride thereon until it is supported by the periphery of the lifter cam 47, rotating the rocker 31 about its pivot 36 and moving the contact bar in position 21a to circuit-completing position 21 across the contacts 20. As soon as the rocker end 42 has ridden up upon the periphery of lifter cam 47, the pin 53 comes into contact with the other end of slot 54 and causes the breaker cam 48 to rotate sufficiently to bring its periphery under the rocker end 42, thus placing the cams in position to commence another cycle of operation when the elevator again strikes the roller 84.

The structure just described has been assembled for use as a quick-break switch where the circuit is normally complete between contacts 20. By reversing the springs 63 and 70 so that they will tend to rotate the shaft 58 in the opposite direction and likewise reversing the stop lever 73, the switch will be assembled to maintain the circuit normally broken, rather than normally complete, while by omitting the springs 25 altogether the switch may be brought to circuit-completing or circuit-breaking position and remain in either position until the lever is moved to bring it to the opposite direction.

In the form shown in Fig. 5, the same principles are shown diagrammatically as applied to a switch consisting of straight levers and straight cams, rather than the circular cams in the forms shown in Figs. 1 to 4. In this form the rocker 31' pivoted on the fulcrum 36' is lifted by cam arm 47' by movement of the operating lever 81' around the fulcrum 101, thereby causing the bar 102 to force the latch 51' under the lifted end 42' of rocker 31', thus holding the rocker 31' in the position shown in full lines with the contact bar 21' completing the circuit between contacts 20'. Movement of the lever 81' in the opposite direction first lowers the cam 47', then causes bar 102 to move the latch 51' from under the lifted end 42' of rocker 31', whereupon spring 43' 45 forces rocker 31' to quickly raise contact bar 21' from the contact pins 20', thus breaking the electric circuit.

If desired, additional contact pins 120' may be provided at the other end of the movement of the bar 21' so that a circuit may be completed to contacts 120, after the circuit to contacts 20' is broken. Thus when used with an elevator, for instance, the circuit for raising the elevator may be routed through contacts 20', while the circuit for reversing the elevator may be routed through contacts 120'. Spring 63' when placed in the full line position will normally hold the contact bar in circuit-completing position through the contacts 20'. If placed in the dotted line position 163' it will hold the contact bar 21' in normally circuit-breaking position for the contacts 20', while, if omitted altogether, the switch will remain in either position until changed by moving the lever 81'.

In the form shown in Fig. 6, the switch has been modified so as to provide a quick-make as well as a quick-break mechanism. In this form there have been added a pawl 103 urged toward counter-clockwise rotation by a spring 104, a notch 105 on cam arm 147', a pin 106 operable in slot 107 of cam arm 147', and a projection 108 on bar 102. Movement of the bar 81', in Fig. 6, to the position shown by broken lines, causes the switch to break the circuit quickly, the same

as in Fig. 5. In broken-circuit position in Fig. 6 the spring 104 causes pawl 103 to engage in notch 105.

Upon movement of the bar 81' back to the full line position, cam bar 147' is retained by pawl 103 until the projection 108 strikes it, causing it to release pawl 103, whereupon the tension of spring 109 causes the bar 147' to move the rocker 31' quickly to the circuit-completing position shown in full lines.

Other modifications and changes in the proportions and arrangements of the parts may be made by those skilled in the art without departing from the nature of the invention, within the scope of what is hereinafter claimed.

The invention described herein may be manufactured and/or used by or for the Government of the United States of America for governmental purposes without the payment of any royalties thereon or therefor.

Having thus set forth and disclosed the nature of this invention, what is claimed is:

1. A limit switch mechanism comprising terminal contact means, a switch member adapted to be moved into and out of engagement with said contact means, a rocker means, yieldable means insulatably supporting said switch member on said rocker means, cam means operable in one direction to rock said rocker toward circuit-completing position and then hold it in such position, yieldable means urging said rocker toward circuit-breaking position on operation of said cam means in the opposite direction, said cam means including a cam member for gradually rocking said rocker toward circuit-completing position, and a second cam member supporting said rocker in circuit-completing position after said first cam member is initially withdrawn, said second cam member including means to abruptly release said rocker to circuit-breaking position.

2. A limit switch mechanism comprising terminal contact means, a switch member adapted to be moved into and out of engagement with said contact means, a rocker means, yieldable means insulatably supporting said switch member on said rocker means, cam means operable in one direction to rock said rocker toward circuit-completing position and then hold it in such position, yieldable means urging said rocker toward circuit-breaking position on operation of said cam means in the opposite direction, said cam means including a cam member for holding said rocker in circuit-completing position, a second cam member supporting said rocker in circuit-breaking position.

circuit-completing position after said first cam member is initially withdrawn, said second cam member including means to abruptly release said rocker to circuit-breaking position, yieldable means normally urging said cam means in one direction, and a lever operable by a mechanism to be controlled operating said cam means in the opposite direction.

3. A limit switch mechanism comprising terminal contact means, a switch member adapted to be moved into and out of engagement with said contact means, a rocker means, yieldable means insulatably supporting said switch member on said rocker means, cam means operable in one direction to rock said rocker toward circuit-completing position, yieldable means urging said rocker toward circuit-breaking position on operation of said cam means in the opposite direction, said cam means including a first cam member for moving said rocker to circuit-completing position and holding it in said circuit-completing position, and a second cam member supporting said rocker against rocking operation, lost motion means connecting said cam members together to cause said second cam member to follow said first cam member after said first cam member is initially operated, said second cam member including means to abruptly release said rocker for operation to circuit-changing position.

4. A limit switch mechanism comprising terminal contact means, a switch member adapted to be moved into and out of engagement with said contact means, a rocker means, yieldable means insulatably supporting said switch member on said rocker means, cam means operable in one direction to rock said rocker toward circuit-completing position and then hold it in such position, yieldable means urging said rocker toward circuit-breaking position on operation of said cam means in the opposite direction, said cam means including a lifter cam member for rocking said rocker toward circuit-completing position and for holding said rocker in circuit-completing position, and a breaker cam member, lost motion means connecting said cam members together to cause said breaker cam member to follow said lifter cam member after said lifter cam member is operated, said breaker cam member including means to also support said rocker in circuit-completing position until after said lifter cam is initially operated and to then abruptly release said rocker to circuit-breaking position.

MARION E. WEEKS.
